Primary Examiner — Mark Goodwin(74) Attorney, Agent, or Firm — Aleya Champlin; Arlene Hornilla(57) CLAIM

We claim the ornamental design for packaging for dough product, as shown and described.

DESCRIPTION

FIG. 1 is a perspective view of a packaging for dough product showing our new design;

FIG. 2 is a top plan view thereof;

FIG. 3 is a top plan view of a modified form thereof;

FIG. 4 is an end view thereof;

FIG. 5 is an end view of a second embodiment of a packaging for dough product showing our new design;

FIG. 6 is a side view thereof; and,

FIG. 7 is a top plan view thereof, the broken line showing a second packaging being shown for illustrative purposes only.
